UNITED STATES PATENT OFFICE.

WILLIAM S. MENDEN, OF BROOKLYN, NEW YORK, ASSIGNOR TO MEGOSIN COMPANY, INC., A CORPORATION OF NEW YORK.

AUTOMATIC SWITCH-CONTROLLING MEANS.

1,149,207.

Specification of Letters Patent. Patented Aug. 10, 1915.

Original application filed December 2, 1913, Serial No. 804,224. Divided and this application filed November 3, 1914. Serial No. 870,121.

To all whom it may concern:

Be it known that I, WILLIAM S. MENDEN, a citizen of the United States, residing in the borough of Brooklyn, county of Kings, 5 and State of New York, have invented certain new and useful Improvements in Automatic Switch-Controlling Means, of which the following is a full and clear specification.

10 This invention relates to automatic switch controlling means and constitutes a divisional part of my co-pending application filed December 2nd, 1913, Serial Number 804,224, in which the present invention 15 is shown in its adaptation to a system for switching on and off the illuminating lights of a vehicle.

20 The primary object of the present invention is to provide an improved construction 25 and arrangement of parts in switch-controlling apparatus for successively and periodically changing the conditions in an electric circuit.

One of the objects of this invention is 30 to provide improved switch controlling apparatus which depends upon the co-operative action of two independently operated instrumentalities.

Other and further objects will appear in 35 the specification and be pointed out in the appended claims, reference being had to the accompanying drawings, in which,—

Figure 1 is a vertical section of one embodiment of my invention corresponding 40 to the line I—I, Fig. 2, parts being shown in elevation; Fig. 2 is a section on the line II—II, Fig. 1, parts being shown in elevation; Fig. 3 is a fragmentary detail showing means for releasably locking the contact 45 wheel in predetermined positions, parts being broken away and parts shown in section; Fig. 4 is a side elevation of a contact wheel on an enlarged scale, parts being shown in section; Fig. 5 is an axial section 50 of Fig. 4, parts being broken away and parts shown in elevation.

Referring more particularly to the drawings and for the sake of convenience, confining the description to the preferred embodiment shown thereon, a housing 1 is provided with a boss 2 as shown in Fig. 2, which carries a bolt 3 upon which is journaled the hub 4 of a contact wheel to be presently described. Integral with the hub

4 is a toothed wheel 5 which is adapted to have a certain angular movement periodically imparted thereto in the manner to be hereinafter pointed out. As shown in Fig. 5, the hub 4 of the wheel is provided with an annular recess 6 at one end extending around the bolt 3 to accommodate a spring 7, which is interposed between the inner end of the recess 6 and the head 8 of the bolt 3. The outer end of the recess 6 is enlarged at 9 to accommodate the head 65 8 of the bolt. As shown in Fig. 4, a plurality of rigid arms 10 project radially from the hub 4 at regular intervals. Immediately of said arms 10, the hub 4 is provided with a plurality of pairs of spaced 70 bearing lugs 11 (see Fig. 5), said lugs being provided with shoulders 12 against which the pins 13 carried by the inner ends of the movable arms 14, abut. The inner end of each of the movable arms 14 is 75 pivotally mounted between the bearing lugs 11 by means of a pin or rivet 15. As shown in Figs. 2 and 5, the outer ends of the arms 14 carry contacts 16 which are suitably rounded, as shown in Fig. 2, which releasably engage in a hollow seat 17 formed in a fixed contact 18 (see Fig. 3) which is secured by rivets 19 to a block 20, said block being secured by bolts 21 to the wall 80 of the housing 1. As shown in Fig. 2, the fixed contact 18 is provided with an integrally formed post 22, to which is secured the end of an insulated wire 23, said wire being introduced into the housing through a bushing 24. The contacts 16 on the outer 85 ends of the fixed radial arms 10 are suitably insulated from the hub 4, so that when said contacts come into engagement with the fixed contact 18, the circuit will be broken. As shown in Fig. 4, each of the fixed arms 90 10 carries at its outer extremity an eyelet 25 to which one end of a spring 26 is secured. The other end of said spring is secured to an eyelet 27 carried by the outer 95 end of each of the movable arms 14, the purpose of said spring being to normally and yieldably retain the pin 13 against the shoulder 12. The resilient action of the spring 7 during the rotary movement of the wheel permits the contacts 16 to move 100 into and out of engagement with the fixed contact 18. During those movements in which the movable arms 14 are withdrawn

from the fixed contact 18, the springs 26 permit said arms to remain for a short period of time in the hollow seat 17 when the increased tension of the spring, together with the movement of the wheel, makes the circuit breaking operation abrupt so as to prevent undue flashing across the contacts.

In Fig. 2, of the drawings is shown a block 28 which is secured to the housing 1 by means of bolts 29. Integral with this block is a bracket arm 30 which constitutes one of a pair of the same as shown in Fig. 1. Within these bracket arms is reciprocably mounted a bar 31 which is provided with a socket 32 at one end to receive the rounded extremity of a bolt 33 which is reciprocably mounted in a socket 34 which is secured to the outer wall of the housing. Interposed between a collar 35 on the inner end of said bolt 33 and the end of the socket 34, is a spring 36 which normally retains the bar 31 in the position shown in Fig. 1. The other end of the bar 31 carries a cam roller 37 which is adapted to ride over a cam block 38 carried on the outer end of a radial arm 39 which is keyed to the inner end of a bolt 40, said bolt being journaled in a bushing 41 mounted in the wall of the housing 1. A depending lever arm 42 is keyed to the outer end of the bolt 40 and is adapted to be engaged by any suitable instrumentality for throwing the cam block 38 against the cam roller 37. Suitable and efficient means for retaining cam block 38 and lever arm 42 in normal central position, are provided by a deflected arm 43 which is mounted upon a rod 44 and provided with means for resiliently supporting it against the movement of a pin 45 which projects laterally from the radial arm 39. A pawl 46 for transmitting motion from the reciprocating bar 31 to the rotary toothed wheel 5 is pivoted on a pin 47 carried by the bar 31. Integral lugs 48 on the pawl 46 serve to limit its motion in opposite directions on the pin 47. Said pawl is provided with a spur 49 which is adapted to fit into the spaces between the teeth 5, said teeth being rounded as shown in Fig. 1, to suitably engage the spur 49 when moving in one direction, and to displace said spur when said bar moves in the opposite direction. Said pawl is also provided with an offset tail 50 which is adapted to be engaged by a pin 51, which as shown in Fig. 2, is carried by an oscillatory arm 52 which is mounted on a pivot 53 carried by a strap 54 mounted on a plunger 55, said plunger being reciprocably mounted in bosses 56. The lower end of the plunger 55 preferably carries a roller 57, adapting it to be displaced by any suitable instrumentality. Adjacent to the plunger 55 is mounted a fixed rod 58 extending between the opposite

walls of the housing 1. Said plunger 55 carries a strap 59 which extends on opposite sides of the fixed rod 58 and serves to support one end of a spring 60, the other end of said spring being in abutment with the wall of the housing 1 and serving to normally retain the plunger 55 in depressed position. The arm 52 is provided with an eyelet 61 as shown in Fig. 2, to which one end of a spring 62 is secured, the other end of said spring being secured to a strap 63 which is carried by the plunger 55. A tail piece 64 carried by the arm 52 serves to limit its upward movement under the tension of spring 62. As shown in Fig. 2, the outer wall of the housing 1 is provided with a binding post 65 to receive a wire 66 which leads from the controlling apparatus.

The operation of my improved apparatus will now be readily understood and briefly described as follows: Suppose the circuit to be broken; in this case one of the fixed arms 10 will be in position to bring the insulated contact on its outer end against the fixed contact 18 of Fig. 3. If, under these conditions, the circuit is to be established, some suitable instrumentality effects an upward displacement of the plunger 55. Thereupon the pin 51 is yieldably forced against the tail 50 of the pawl 46 until the spur 49 engages one of the teeth 5. Immediately a suitable instrumentality displaces the lever arm 42, thus forcing the cam 38 against the cam roller 37 to effect a displacement of the bar 31 toward the right according to Fig. 1. This movement is sufficient to rotate the contact wheel a suitable distance to remove the insulated contact and to bring the conducting arm 14 into position in which the contact carried thereby engages the fixed contact 18. This establishes the circuit, said circuit remaining thus until a subsequent operation of the plunger 55 and lever arm 42 produces another angular movement of the contact wheel. The operations of the remaining parts are evident from the foregoing description, as well as the showing made on the drawings, and need not be further referred to.

Obviously, various modifications in the construction and arrangement of parts may be embodied without departing from the broad spirit of my invention.

I claim:

1. The combination of an energizing circuit including a circuit closing instrumentality rotatable about an axis, said instrumentality being provided with radially disposed insulating and conducting arms alternately arranged, and means for periodically imparting a part rotation to said instrumentality to successively make and break said circuit.

2. The combination with an energizing circuit including a circuit closing instru-

mentality rotatable about an axis, said instrumentality being provided with radially disposed insulating and conducting arms alternately arranged, and means for periodically imparting a part rotation to said instrumentality to successively make and break said circuit, said means including a toothed wheel secured to said instrumentality, a reciprocable bar, a pawl mounted on said bar, and automatic means for moving said pawl into and out of engagement with said toothed member.

3. In a device of the character described, a rotary circuit making and breaking instrumentality, an energizing circuit including the same, means for periodically imparting a limited angular movement to said instrumentality, said instrumentality being provided with a plurality of radially mounted insulated contacts and intermediately thereof of a plurality of conducting contacts, said circuit being provided with a fixed contact into engagement with which are brought the insulated and conducting contacts on the rotary instrumentality alternately.

4. The combination with an energizing circuit provided with a pair of fixed contacts, a journal connected to one of said contacts, a wheel journaled thereon and in conducting relation thereto, said wheel being provided with a plurality of radial arms having insulated contacts on their outer extremities, and a plurality of arms arranged intermediately thereof provided with circuit making contacts on their outer extremities, and automatic means for periodically imparting a limited angular movement to said wheel, said means being adapted to successively move said contacts into and out of engagement with the other fixed contacts of said energizing circuit.

5. The combination with an energizing circuit provided with a pair of fixed contacts, a journal connected to one of said contacts, a wheel journaled thereon and in conducting relation thereto, said wheel being provided with a plurality of radial arms having insulated contacts on their outer extremities and a plurality of arms arranged intermediately thereof provided with circuit making contacts on their outer extremities, and automatic means for periodically imparting a limited angular movement to said wheel, said means being adapted to successively move said contacts into and out of engagement with the other fixed contacts of said energizing circuit, said means for moving said wheel comprising a movable member normally disengaged from said wheel, and another movable member for establishing an engaging connection between the face of said member and said wheel.

6. The combination with an energizing circuit provided with a pair of fixed contacts, a journal connected to one of said contacts,

tacts, a wheel journaled thereon and in conducting relation thereto, said wheel being provided with a plurality of radial arms having insulated contacts on their outer extremities and a plurality of arms arranged intermediately thereof provided with circuit making contacts on their outer extremities, and automatic means for periodically imparting a limited angular movement to said wheel, said means being adapted to successively move said contacts into and out of engagement with the other fixed contacts of said energizing circuit, said means for moving said wheel comprising a movable member normally disengaged from said wheel, and another movable member for establishing an engaging connection between the face of said member and said wheel, said wheel being yieldably mounted to move longitudinally of its axis.

7. In a device of the character described, a rotary wheel provided with a plurality of rotary projecting arms provided with contacts at their outer extremities, a contact conductively connected to the contacts on every other arm of said wheel, means for insulating the contacts on the other arms, means for periodically imparting a limited angular movement to said wheel, a fixed contact into engagement with which the contacts on said wheel are successively moved and an energizing circuit including said fixed contacts.

8. In a device of the character described, a rotary wheel provided with a plurality of rotary projecting arms provided with contacts at their outer extremities, a contact conductively connected to the contacts on every other arm of said wheel, means for insulating the contacts on the other arms, means for periodically imparting a limited angular movement to said wheel, a fixed contact into engagement with which the contacts on said wheel are successively moved and an energizing circuit including said fixed contacts, the arms of said wheel which carry the circuit conducting contacts being yieldably mounted.

9. In a device of the character described, the combination with a rotary hub, a fixed contact, a plurality of radially projecting arms rigid with said hub, said arms being provided with contacts insulated from said hub, other radial arms arranged intermediately of said first named arms and pivotally connected to said hub, the last mentioned arms being provided with contacts conductively connected to said hub, yieldable means connecting each of said pivot arms to one of said fixed arms, an energizing circuit including said hub and said fixed contact, and means for periodically imparting an angular movement to said hub equal to the distance between adjacent arms carried thereby.

10. In a device of the character described,

the combination with a rotary hub, a fixed contact, a plurality of radially projecting arms rigid with said hub, said arms being provided with contacts insulated from said hub, other radial arms arranged intermediately of said first named arms and pivotally connected to said hub, the last mentioned arms being provided with contacts conductively connected to said hub, yieldable means connecting each of said pivot arms to one of said fixed arms, an energizing circuit including said hub and said fixed contact, and means for periodically impart-

ing an angular movement to said hub equal to the distance between adjacent arms carried thereby, said hub being provided with an axial recess and a bore concentric thereto, and a fixed bolt passing through said bore and carrying a spring interposed between the head of said bolt and the inner wall of said recess.

WILLIAM S. MENDEN.
